UNITED STATES PATENT OFFICE.

ALBERT A. MARTELL, OF WOONSOCKET, RHODE ISLAND, ASSIGNOR TO THE TAFT-PEIRCE MANUFACTURING COMPANY, OF WOONSOCKET, RHODE ISLAND, A CORPORATION OF RHODE ISLAND.

MACHINE REAMER.

Application filed May 12, 1922. Serial No. 560,361.

To all whom it may concern:

Be it known that I, ALBERT A. MARTELL, a citizen of the United States, residing at Woonsocket, in the county of Providence, State of Rhode Island, have invented certain new and useful Improvements in Machine Reamers, of which the following is a specification.

The present invention relates broadly to small tools and more specially to a reamer.

Heretofore in the art it has been customary to prepare reamer bodies with grooves or the like to receive blades and to constitute the supporting and guiding means for such blades. Reamers are now used for very accurate work and therefore must be made to very precise dimensions. In the use of reamers it may be necessary to adjust the blades on the blade seats and there is a liability of wear on these seats. Furthermore where the metal in the seat for the blade is soft it is not possible to finish the metal to the accurate dimensions or surface which may be obtained by the use of hard metal. In the manufacture of such reamers it is necessary that substantially the final shape of the reamer body be made before the hardening process can be undertaken otherwise the cost of manufacture becomes so high as to be prohibitive. Attempts have been made to harden the reamer body after it has been rough finished but it is exceedingly difficult to harden the slots properly and then to properly grind the slots after the hardening has been performed. To this end it has been customary to provide some additional member of hard metal which can be placed in the slot and used as a seat for the blade. Such members are shown as wedges in my prior Patent No. 1,193,583, Aug. 8, 1916.

Furthermore it has been found that after a reamer body has been made to accurate dimensions and is then hardened that the hardening operation distorts the body and causes changes in the form of the blade receiving slots which destroys the accuracy of the tool.

The present invention comprises a reamer in which the difficulties of the known art are overcome by providing a reamer body having a relatively large driving portion adjacent an adjusting ring portion which

carries the blade supporting member of the reamer. The blade supporting member 55 comprises the frustum of a cone which is shaped to substantially a desired form and is provided with grooves to receive blade supporting clamps. After the blade supporting portion is shaped it is hardened and 60 then ground and lapped to a smooth glass-hard surface. The blades which are adapted to set on the glass-hard surface, have a front side terminating in a cutting edge with a base at right angles to the front 65 side and a tapered back, as well as an inclined bottom portion. These blades are hard metal and the bottom surfaces thereof are also finished to a glass-hard finish in the form substantially of a plane. Clamp 70 blocks provided with tongues are set on the frusto-conical portion to the body and are adapted to cooperate with the sides of the blades to clamp the bases of the blades against the glass-hard conical body surface. 75 Suitable screws pass through the center lines of the clamp blocks and when tightened securely hold the blades in position. The clamp blocks are so arranged that the blades are set in pairs with the blades of one pair 80 inclined in the same direction and blades of other pairs inclined in another direction. Suitable adjustment nuts are provided on the body of the reamer to support the ends of the blades during the reaming operations. 85 These adjustment nuts abut against the ends of the reamer blades which are finished to lie in a plane substantially at right angles to the axis of the reamer so that there is no overhang to the adjustment nuts relatively to the blades. This facilitates the manufacture of the reamer body in that it is not necessary that the screw threads for the nuts shall be absolutely concentric with the axis of the reamer as any eccentricity 95 in the rotation of the adjustment nuts does not affect the accuracy of the seating of the reamer blades. The foregoing general description shows that the present reamer may be produced in a very economical manner and at the same time the reamer is 100 exceedingly accurate and comprises an instrument of precision.

Having generally described the present invention it may be stated that the principal 105 object thereof is to provide a reamer having

a hardened blade supporting portion adapted to form the seat for hardened blades and with the parts arranged in such manner as to be capable of adjustment.

5 Another object of the present invention is a reamer of the character specified and wherein the adjustment nuts for the blades are provided with surfaces at right angles to the ends of the blades so that eccentricity 10 in the nuts does not affect the accuracy of the blades.

A still further and important object of the present invention is a reamer of the character specified and wherein the body 15 is provided with a driving head of relatively large size to facilitate the application of power in driving the reamer.

A still further object of the present invention is a reamer of the character specified 20 and wherein the reamer blades are formed with substantially plane bottom surfaces, and the reamer body is formed by the frustum of a cone which is accurately formed with a glass-hard surface.

25 Other and further objects of the present invention will in part be obvious and will in part be pointed out hereinafter by reference to the accompanying drawings wherein like characters are used to represent like parts throughout the several figures thereof. It is realized that the present inventions 30 may be embodied in constructions other than those specifically shown so therefore it is desired that the disclosure shall be considered as illustrative and not in the limiting sense.

Referring now to the drawings, Figure 1 illustrates the assembled reamer;

40 Figure 2 is an end view of the assembled reamer looking at the ends of the blades;

Figure 3 is a side view of the body portion;

Figure 4 is a front elevation of the body portion;

45 Figure 5 is a rear elevation of the body portion;

Figure 6 is a view illustrating one of the blades;

50 Figure 7 is a view illustrating one of the clamp members.

For more detailed description of the reamer attention is directed to the drawings, wherein is illustrated the reamer body which is provided with a driving head 1 55 that is provided with interlocking driving slots 2 that cross the reamer shaft opening 3 that extends through the body of the reamer. A threaded portion 4 is next adjacent the drive and carries the blade supporting portion 5. The blade supporting portion 5 is separated from the threaded portion 4 by a groove 6 and is substantially in the form of the frustum of a cone with the base of the frustum toward the 60 outer end of the body. This conical por-

tion of the body may be hardened, or if desired, the entire body may be hardened and the blade supporting portion finished to very accurate dimensions in order to comprise an accurate seat for the blades. 70 Before the hardening process takes place the portion 5 is provided with slots 7 which may be milled or otherwise cut in the body portion. Suitable screw threaded openings 8 are provided through the milled slots in 75 order to receive machine screws 9 as will later be described. After the body portion is finished adjustment nuts are provided and a lock nut 10 is slipped over the portion 6 and screw threaded on portion 4 toward the driving head 1. The adjustment nut 11 is then similarly positioned on portion 4 and brought substantially in contact with the lock nut. Both nuts are provided with 80 openings 12 adapted to receive a spanner wrench or the like in order to adjust the nuts. Clamp blocks 13 are positioned over the blade carrying portion 5 with tongues 14 interlocking with the slots 7 and are secured in place by stub screws 9 which pass through clamp blocks and are screw threaded into the openings 8 in the body portion 5. Blades are slipped between clamp blocks before the blocks are tightened and these 85 blades are provided with a cutting face 15 and a plane base 16 which is accurately formed and hardened and which is tapered relatively to the cutting face in order to provide a tapered base to rest upon the blade supporting portion 5 so that the 90 reamer may be adjusted by sliding the blades upon the body portion 5. The side 95 17 opposite to the cutting face is inclined in order to provide a surface on which the overhang of the clamp blocks may operate 100 to clamp the blades tightly against the body portion. The blades may be slightly inclined to the axis of the reamer as shown in Figures 1 and 2. In such case the line 105 of contact of the blade with the conical support 5 is substantially parallel to the axis of the reamer and extends diagonally across the base of the blade; that is, the line of contact on the base of the blade is not 110 parallel to the side of the blade.

115 From the foregoing construction it will appear that a proper rotation of the adjustment nut in contact with the ends of the blades 14 will slide the blades upwardly on the conical surface of the blade supporting member 5, therefore expanding the reamer, and a movement in the opposite direction 120 will permit the blades to be shoved inwardly so that the diameter of the reamer will be diminished. In view of the fact that the body portion and the blades are very accurately made this expansion may be accurately determined by caliperizing across one pair of blades and since the body portion 125 is hardened and ground as well as the 130

base portion of the blades being hardened and ground, the accuracy of the tool is maintained over a relatively long life.

Having thus described my invention, what

5 I claim is:

1. A reamer comprising a body portion; a conical blade supporting member comprising the end of the body portion; blade clamp grooves in said conical member with the axis of said grooves being substantially parallel to the axis of the body portion; blade clamps with the sides thereof inclined relatively to the axis of the body portion; tongues on said blade clamps adapted to set in said grooves; means to hold said clamps in position in said grooves; and wedge shaped blades adapted to be seated against said conical member by said blade clamps. 10
2. A reamer comprising a body portion; a conical blade supporting member comprising a part of the body portion; blade clamp grooves in said conical member with the axis of said grooves being substantially parallel to the axis of the body portion; blade clamps with the sides thereof inclined relatively to the axis of the body portion; tongues on said blade clamps adapted to set in said grooves to maintain said blade clamps accurately aligned in the conical member; means to move said blades radially; means to hold said clamps in position in said grooves; and blades adapted to be seated against said conical member by said blade clamps. 15
3. A reamer comprising a body portion; a conical blade supporting member comprising a part of the body portion; blade clamp grooves in said conical member with the axis of said grooves being substantially parallel to the axis of the body portion; blade clamps with the sides thereof inclined relatively to the axis of the body portion; tongues on said blade clamps adapted to set in said grooves; means to hold said clamps in position in said grooves; and blades adapted to be seated against said conical member by said blade clamps. 20
4. A reamer comprising a body portion; a conical blade supporting member comprising the end of the body portion; blade clamp grooves in said conical member with the axis of said grooves being substantially parallel to the axis of the body portion; blade clamps with the sides thereof inclined relatively to the axis of the body portion; tongues on said blade clamps adapted to set in said grooves; means to hold said clamps in position in said grooves; and wedge shaped blades adapted to be seated against said conical member by said blade clamps, the bases of said blades being planes. 25
5. A reamer comprising a body portion; a conical blade supporting member comprising the end of the body portion; blade clamp grooves in said conical member with the axis of said grooves being substantially parallel to the axis of the body portion; blade clamps with the sides thereof inclined relatively to the axis of the body portion; tongues on said blade clamps adapted to set in said grooves; and wedge shaped blades adapted to be seated against said conical member by said blade clamps, the bases of said blades being planes. 30
6. A reamer comprising a body portion; the frustum of a cone on said body portion and comprising a blade supporting member; blades provided with a plane base adapted to set on said blade supporting member; and means to dispose said blades on said member in angular relation to the axis of the body in such manner that the line of contact between the base of said blade and said member is adjacent the back of the advancing end of the blade and is adjacent the front of the other end of the blade with the blades set at different angles relatively to the axis of the said cone. 35
7. A reamer comprising a body portion; the frustum of a cone on said body portion and comprising a hardened polished blade supporting member; blades provided with a plane base adapted to set on said blade supporting member and adapted to set with a full length line contact on said member, and means to dispose said blades on said member in angular relation to the axis of the body in such manner that the line of contact between the base of said blade and said member is adjacent the back of the advancing end of the blade and is adjacent the front of the other end of the blade with the blades set at different angles relatively to the axis of the said cone. 40
8. A reamer comprising a body portion, a driving head on one end of said body portion, a cylindrical threaded portion, a blade supporting portion integral with the driving head, comprising a frustum of a cone with the small end of the frustum substantially adjacent the threaded portion, wedged shaped blades on said conical supporting portion, clamps securely fastened to said blade supporting portion to engage the wide portion of said wedged shaped blades and hold them rigidly in position, and an adjustment nut on said threaded portion adapted to engage and move said blades along said frustum of the cone independently of the position of the other elements of the reamer to adjust said blades radially. 45
9. A reamer comprising a body portion, a driving head on one end of said body portion, a cylindrical threaded portion on

- the outer surface of the body and adjacent to the driving head, a blade supporting portion integral with the body portion and comprising the frustum of a cone with the small end of the frustum being substantially adjacent the said threaded portion, blades on said supporting portion, clamps bolted to said supporting portion between said blades to hold said blades in a radial and lateral position on said support, and an adjustment nut on said threaded portion adapted to engage and move said blades along said conical supporting portion independently of the other elements of the reamer to adjust said blades radially.
10. In a reamer, a blade supporting member comprising the hardened frustum of a cone, blades mounted upon said supporting member at angles to the axis thereof, the bases of said blades being substantially planes adapted to form line contacts with said supporting member, and means to securely hold said blades in position on said supporting member.
20. 11. In a reamer, a blade supporting member comprising the hardened frustum of a cone, blades mounted upon said supporting member at angles to the axis thereof, the bases of said blades being substantially planes adapted to form line contacts with said supporting member, means to securely hold said blades in position on said supporting member, and means to adjust the blades on said cone.
25. 12. A reamer comprising a blade support in the form of the frustum of a cone, wedge shaped blades mounted on said support with

the bases of said blades comprising substantially plane surfaces, devices to adjust the blades longitudinally on the cone and means to angularly dispose said blades relatively to the axis of the reamer, said means being adapted to clamp said blades tightly against the blade support in such manner that the line of contact with said blades and said support is substantially parallel to the axis of the reamer.

13. A reamer comprising a blade support in the form of the frustum of a cone, blades mounted on said support with the bases of said blades comprising substantially plane surfaces, devices to adjust the blades longitudinally on the cone and means to angularly dispose said blades relatively to the axis of the reamer, said means being adapted to clamp said blades tightly against the blade support in such manner that the line of contact with said blades and said support is substantially parallel to the axis of the reamer.

14. A reamer comprising a blade support in the form of the frustum of a cone, wedge shaped blades mounted on said support with the bases of said blades comprising substantially plane surfaces, and means to angularly dispose said blades relatively to the axis of the reamer, said means being adapted to clamp said blades tightly against the blade support in such manner that the line of contact with said blades and said support is substantially parallel to the axis of the reamer while the cutting edges of the blades are angular to the said axis.

ALBERT A. MARTELL.
